UNITED STATES PATENT OFFICE.

WALTER S. HARRISON, OF TABOR, SOUTH DAKOTA.

EAR-CORN CONVEYER.

No. 920,951.

Specification of Letters Patent.

Patented May 11, 1909.

Application filed October 3, 1907. Serial No. 395,756.

To all whom it may concern:

Be it known that I, WALTER S. HARRISON, a citizen of the United States, residing at Tabor, in the county of Bonhomme, State of 5 South Dakota, have invented certain new and useful Improvements in Ear-Corn Conveyers; and I do hereby declare the following to be a full, clear, and exact description of the invention, such as will enable others 10 skilled in the art to which it appertains to make and use the same.

This invention relates to new and useful improvements in ear corn conveyers for corn shelling machines and it has more particular 15 reference to a conveyer comprising endless chains provided with gathering hooks and co-operating with an elevator which discharges into a chute or spout, the latter being employed to transfer the corn to the shelling 20 machines.

The invention aims as a primary object to provide a novel construction, combination and arrangement of parts, the details of which will appear in the course of the following description in which reference is had to the accompanying drawings, forming a part 25 of this specification, like characters of reference designating similar parts throughout the several views, wherein:

30 Figure 1 is a side elevation of a conveyer constructed in accordance with the present invention. Fig. 2 is a top plan view thereof. Fig. 3 is a central longitudinal sectional view thereof. Fig. 4 is an enlarged fragmentary 35 side elevation showing in detail a hand lever mounted at the front end of conveyer. Fig. 5 is a section on the line 5—5 of Fig. 2. Fig. 6 is a detailed view showing the construction and mode of assemblage of a preferred form 40 of gathering hook. Fig. 7 is a similar view of a modified form of gathering hook.

In the accompanying drawings, the numeral 10 designates generally the elevator frame comprising a rectangular base 11, 45 which has connected thereto near one end of the same vertical posts 12, the latter, together with the front ends of the side bars of the base 11, supporting inclined bars 13 constituting the side bars of the elevator proper, 50 the latter comprising transverse cleats 15, supported by parallel chains 16, the cleats 15 having connection with said chains at suitable equi-distant points. The bars 12 are braced at their upper ends by a cross piece 17 55 and below the cross piece 17 are provided

with suitable bearings for a transverse shaft 18, the latter carrying on the inner side of the posts 12 sprocket wheels 19, over which the chains 16 are trained. The chains 16 are likewise trained under sprocket wheels 20 60 mounted on stub shafts 21 at the lower ends of the bars 13, and over sprocket wheels 22 arranged at the ends of the side bars of the base 11, the said sprocket wheels 22, being mounted on a transverse shaft 24. Adjacent the 65 sprocket wheels 20, idler sprocket wheels 25 mounted on stub shafts 26 are provided, the sprocket wheels 25 bearing against the upper laps of the chains 16 and serving as guides therefor, whereby said chains may be 70 turned from an inclined line of travel to a horizontal line of travel.

The side bars near the front end of the base 11 support short vertical posts 27 connected at their upper ends by a cross bar 28 and reinforced by diagonal braces 29 secured thereto and to the said side bars of the base 11. The bar 28 is provided at one side thereof with a bearing 30 through which projects a longitudinal shaft 31, the latter likewise projecting through bearing sleeves 32 formed on a bracket 33, the latter being secured to one of the posts 12 and being formed as a bearing for a stub shaft 34 disposed at right angles to the shaft 31 and carrying a bevel 80 pinion 35 which meshes with and is driven from a smaller bevel pinion 36 carried upon the shaft 31. The end of the shaft 31 projects into a horizontal sleeve 37 constituting a bearing therefor, and connected by a web 85 38 with a vertical sleeve 39, the latter surrounding a drive shaft 40 in gear with the corn shelling mechanism. The sleeve 39 is provided with an arm 41 of substantial L 90 shape and including an upwardly extending 95 portion to which is secured a collar 42 the latter serving as a stop and also as a bearing for the hub 43 of a bevel pinion 44, the latter being arranged at the end of the sleeve 37 and being in mesh with and driven from a similar pinion 45 provided on the shaft 40.

The hub 43 is formed with a clutch face 46 and splined upon the shaft 31 for sliding movement is a clutch yoke 47 formed with a circumscribing groove 48 in which is engaged the yoked end 49 of a pivoted hand lever 50, the latter working about a rack quadrant 51 and being provided with a trigger operated pawl 52 for engagement with the teeth of said rack quadrant. The shaft 31 at its 110

front end, has connection by means of universal or gimbal joint 53 with a short length shaft 54, journaled in a casting 57 and carrying a bevel pinion 58.

- 5 The gathering mechanism comprises a rectangular box-like frame 59 strengthened by interior reinforcing (not shown) and including vertical side walls 60 and end walls 61. To one end of the end walls 61, bearings 10 62 are secured, the latter being provided for a vertical shaft 63 which projects through a sleeve 64 forming a part of the casting 57 and which carries a bevel pinion 65 in mesh with and driven from the pinion 58. The shaft 15 63 projects downwardly and is designed for detachable engagement in a bearing 66, secured to the rear end of the base 11. The box-like frame 59 also includes top and bottom walls 67 and 68 which project beyond 20 the side walls and are formed with opposed inwardly extending portions 69 coacting with said side walls to afford upper and lower grooves 70 and 71 through which upper and lower chains 72 and 73 have movement, the 25 chains 72 and 73 traveling entirely around the frame 59 and being trained over upper and lower sprocket wheels 74 and 75 arranged at the end of said frame, the sprockets 74 and 75 being carried upon the shaft 63. 30 Secured to the bottom wall 68 at one side thereof, is a laterally projecting trough 77 having a slanting bottom 78.

The chains 72 and 73 conjointly support a plurality of gathering hooks 79 of novel construction and illustrated more particularly in Fig. 6, in which a curved member 80 is shown that constitutes the hook proper. The member 80 is of angle iron construction and has its angularly curved end pointed as at 81. 35 At its other end, said member is formed with a horizontal lug 82, by means of which said member is secured to a link of the chain 71, the portion 82 lying against one side of the said link. The lug 82 is connected to said 40 link by means of a vertical pin 83, the pin 83 serving as a pintle for a friction roller 84 which rests upon the base of the groove 71 and bears against the sides thereof. The hooked member 80 constructed and assembled 45 with relation to the chain 73 in this manner, has fixed connection with a member 85 which includes a vertical portion 86 terminating at its upper end in an angular lug 87 which is secured to one of the links of the 50 chain 72. The member 85 also includes a rearwardly extending bow-shaped curved portion 88 which projects in a horizontal plane from the point of connection of the member 85 with the member 80 and which at 55 its rear end, is designed to bear against the outer faces of the portions 69 as a brace. 60

In Fig. 7, there is illustrated a modified form of gathering hook, such form comprising a member 89 of angle iron shape and formed 65 at one end with a lug 90, similar in construc-

tion and for a similar purpose to the lug 82. The member 89 has its body bow-shaped as at 91 and then curved rearwardly and bent into hook form as at 92, the major curved portion of the hooked end 92 bearing against the portions 69. The member 89 has rigid connection adjacent its portion 92 with a vertically extending member 93 terminating in a lug 94 similar to the lug 87 and designed for connection with one of the links of the chain 72. Secured to the rear end of the base 11, is a chute 95 constructed with a recess 96 to surround the shaft 63, the chute 95 being provided to transfer coin from the trough 77 to the elevator 14, which in turn 70 discharges into a lateral downwardly inclined 75 transferring chute or spout 97, through which the coin gravitates to the shelling mechanism. 80

The pinion 35 has formed on its hub a sprocket wheel 98, the latter serving, by means of a chain 99, to drive the shaft 18 of the elevator 14, the chain 99 being trained over a sprocket 100, provided on the projecting end of said shaft. 90

Manually operable means are provided for moving the conveyer as an entirety, in its rotatory adjustable movement, over the ground. Projecting laterally from the top and bottom walls 67 and 68 of the frame 59 95 is a bracket 101 of suitable construction to which is pivoted a pointed ground engaging dog 102. The lateral movement of the conveyer is effected by a lever 103 having a pointed ground engaging end 104 and formed 100 in its body with a longitudinal slot 105, through which is engaged a laterally projecting pivot pin 106, carried by the bracket 101. In moving the conveyer the lever 103 is raised until the pivot pin 106 impinges the 105 lower edge of the slot 105 and said lever is then drawn rearwardly and its end 104 engaged in the ground. The lever 103 is then pushed forwardly as far as possible and raised again, such raising being necessary 110 in order that its end 104 may clear the ground when the lever is drawn rearwardly. After each operation of the end 104, the dog 102 is pushed into the ground by the foot so 115 as to prevent the conveyer from working rearwardly under the action of the connected operating parts. 120

It will be understood that the frame 59 and its adjuncts may be detached from the elevator mechanism and its adjuncts by disassembling the members of the gimbal joint 53. The frame 59, by virtue of the manner of its connection with the shaft 63, may be set at selected positions about said shaft as a pivot with relation to the elevator frame 125 through the means described. The gearing described drives the elevator frame and the conveyer chains 72 and 73 simultaneously, irrespective of the position of the frame 59 with relation to the frame 10. 130

The invention is simple in its structural details, inexpensive to manufacture and practical and efficient in use.

From the foregoing description it will be seen that simple and efficient means are provided for accomplishing the objects of the invention, but while the elements herein shown and described are well adapted to serve the functions set forth, it is obvious that various minor changes may be made in the proportions, shape and arrangement of the several parts, without departing from the spirit and scope of the invention as defined in the appended claims.

15 What is claimed is:

1. In a machine of the type set forth, a gathering mechanism including upper and lower endless chains, a curved hook like member secured to the lower chain and a member secured to said hook like member and having connection with the upper chain.
2. In a machine of the type set forth, the combination with upper and lower chains, of a curved hook like member having connection with the lower chain, a member secured to said curved member and having connection with the upper chain, said last named member including a rearwardly projecting

horizontal portion designed to bear against said lower chain as a brace.

3. In an apparatus of the type set forth, an elevator, a gathering mechanism and means for moving said elevator and said gathering mechanism, comprising a bracket fixed to said stationary part of said gathering mechanism, a lever having a slot and having a pointed ground engaging end, and a pivot pin engaged through said slot, as and for the purpose set forth.

4. In an apparatus of the type set forth, an elevator, a gathering mechanism and means for moving said elevator and said gathering mechanism, comprising a bracket fixed to said stationary part of said gathering mechanism, a lever having a slot and having a pointed ground engaging end, a pivot pin engaged through said slot and a ground engaging dog pivoted to said bracket, as and for the purpose set forth.

In testimony whereof, I affix my signature, in presence of two witnesses.

WALTER S. HARRISON.
